SEWING MACHINE

Peter F. Cencer and Fred Whiteman, Detroit,
Mich., assignors to Frank M. Gidion, Detroit,
Mich.

Application September 10, 1949, Serial No. 4,937

Term of patent 14 years

(Cl. D70—1)

To all whom it may concern:

Be it known that we, Peter F. Cencer and Fred Whiteman, citizens of the United States, residing at Detroit, Michigan, in the county of Wayne, have invented a new, original, and ornamental Design for a Sewing Machine, for which the following is a specification, reference being had to the accompanying drawings, forming part thereof, in which:

Fig. 1 is a side elevational view of a sewing machine, showing our new design.

Fig. 2 is a side elevational view thereof from the opposite side.

Fig. 3 is a plan view thereof.

Fig. 4 is a left end elevational view of the sewing machine shown in Fig. 1; and

Fig. 5 is a right end elevational view of the sewing machine shown in Fig. 1.

We claim:

The ornamental design for a sewing machine, substantially as shown.

PETER F. CENCER.
FRED WHITEMAN.
